Primary Examiner — Elizabeth Albert(74) *Attorney, Agent, or Firm* — James M. Weatherly; Cochran Freund & Young, LLC(57) **CLAIM**

The ornamental design for a hydroponic tower, as shown and described.

DESCRIPTION

FIG. 1 shows a perspective view of a hydroponic tower showing my new design;

FIG. 2 shows a front elevation view thereof;

FIG. 3 shows a back elevation view thereof;

FIG. 4 shows a left side elevation view thereof;

FIG. 5 shows a right side elevation view thereof;

FIG. 6 shows a top plan view thereof;

FIG. 7 shows a bottom plan view thereof; and,

FIG. 8 shows a perspective view thereof.

The broken lines in the drawings illustrate environmental structure on the article that forms no part of the claimed design.

1 Claim, 7 Drawing Sheets(56)
